UNITED STATES PATENT OFFICE.

PAUL KORNAN, OF CHICAGO, ILLINOIS.

DESIGN FOR A LAMP.

Application filed March 1, 1929. Serial No. 30,264. Term of patent 3½ years.

To all whom it may concern:

Be it known that I, PAUL KORNAN, a citizen of the United States and a resident of Chicago, in the county of Cook and State of Illinois, have invented a new, original, and ornamental Design for a Lamp, of which the following is a specification, reference being had to the accompanying drawing, forming part thereof.

The figure is a perspective view of a lamp, showing my new design.

I claim:

The ornamental design for a lamp, as shown.

Signed at Chicago, in the county of Cook, and State of Illinois this 19th day of February, A. D. 1929.

PAUL KORNAN.
